UNITED STATES PATENT OFFICE

JOSEPH V. ROBINSON, OF NEW YORK, N. Y.

AUTOMATIC TRAIN-PIPE CONNECTER

Application filed March 8, 1920, Serial No. 364,253. Renewed March 19, 1929.

My invention relates to automatic train pipe connectors and more especially to that type of train pipe connector with which electricity is employed for the conveyance of signals through the train, or for lighting, heating, telephone, or power purposes. An object of the invention is to provide a simple form of electric terminal or plug which may be readily mounted in the signal port of the train pipe coupling head after the removal from the port of the fittings generally employed with train pipe coupling heads in conveying the air from the signal pipe of the car through the coupling head. Thus my improvement may be applied to the train pipe coupling head at any time without requiring any alteration to the head whatever.

My invention consists of the constructions, combinations and arrangements hereinafter described, pointed out in the appended claims and illustrated in the accompanying drawings in which;

Figure 1 is a side elevation of a train pipe coupling head provided with my improvement.

Figure 2 is a front view of Figure 1.

Figure 3 is an enlarged section taken on the line 3—3 of Figure 2 and showing my improved terminal or plug in elevation.

Figure 4 is a sectional plan view of my improvement showing some of the parts in elevation.

Figure 5 is a rear face view in elevation of the forward member of my improvement taken on the line 5—5 of Figure 4.

Figure 6 is an interior face view of one member of my improvement taken on the line 6—6 of Figure 4 and showing some of the parts in section. In this figure the filler or insulation hereafter described is not shown, and

Figure 7 is a detailed sectional elevation taken approximately on the line 7—7 of Figure 6 and showing the filler as it would appear in this view were it applied in the structure shown in Figure 6.

Referring now to the drawings. Any suitable form of coupling head A having guiding means 8 for bringing the ports of the head into register may be used with my improve-

ment, but I preferably provide a coupling head of the butt face type having vertically aligned orifices as shown in Figure 2, the upper one of which orifices is provided on the side of the head with a hollow nipple 9 which extends rearwardly of the head and preferably at a right angle to the coupling face 10 thereof. Any suitable form of support for flexibly supporting, from the car, a coupling head having my improvement, 55 may be used. I indicate at 11 a suitable form of support which is more fully illustrated in my co-pending application Serial No. 342,-806, filed December 5, 1919.

My improved terminal or plug comprises 65 a body member B made of two separate parts 12 and 13, each of which is constructed of any suitable material which is a non-conductor for electricity such, for instance, as hard rubber. These members are cylindrical in 70 form and are adapted to fit snugly within the upper or signal port 14 of the coupling head A as shown especially in Figure 3, the member 12 being provided with a shoulder 75 15 for mating with the rear wall 16 of the gasket seat 17 in the signal port as shown. The member 13 is provided on its rear side with an enlarged head or base 18 which is adapted to abut the rear face 19 of the nipple 9. To properly position the parts of my improvement in the conduit or port 14, I provide the latter with a groove 20, adapted to snugly receive a projection 21 on the base 80 18 of the member 13. This latter member is provided with a centrally located cylindrical opening 22 which extends through the head or base 18 into a chamber 23 formed in the member 13. Within the centrally disposed opening 22 I force a suitable form of cable or electrical conduit C the wires 24 85 of which are secured within the chamber 23 as by screws 25. These screws are suitably connected with barrels 26 which are firmly locked within the body of the member 13. The screws serve also to lock in position suitable metal posts 27 which extend through a 90 base plate 28 into an opening in the member 13 as shown especially in Figures 4 and 7, the connections between the base plate 28 and the posts 27 and the wires 25 being such 95

100

as to form an electrical connection from such wires through said posts. The member 12 of my improved terminal or plug is provided with barrels 29 rigidly secured in the member 12. Within the barrels and passing through openings in the face 30, which openings are concentric with the openings in said barrels, I provide a pair of plungers 31 formed of non-corrosive material. Into the barrels 29 the aforesaid posts 27 extend when the parts of my improvement are assembled, and between the forward end of these posts and the abutment or head 32 of the plungers 31 I provide suitable springs 33 which serve 10 to maintain the plungers 31 at the limit of their forward movement in the member 12 and which, in connection with the contact between the barrels 29 and the posts 27, and between the barrels and the plungers 31, serve to complete the electrical connection 15 from the wires 24 of the cable C to the forward ends of the plungers 31. To rigidly secure the cable C in place, I preferably press it into the opening 22 of the base 18 and then pour into the hollow 23 of the member 13 wax or other hard substance which is a non-conductor of electricity. Figure 7 illustrates this filling as it would appear when placed. The members 12 and 13 of my improvement 20 are secured together, and the various parts thereof properly positioned through the medium of a pair of screws 34 which extend through the member 13 into a threaded barrel 35 rigidly secured in the member 12 as shown especially in Figures 4, 5 and 6. When thus assembled my improved terminal or plug operates practically as one piece, the joining faces of the members 12 and 13 fitting so closely as to exclude water and other 25 foreign substances from the interior thereof. To assemble my improvement into the port 14 of the coupling head the screws 34 are removed and the member 12 is inserted from the face of the coupling head A and the member 13 is inserted from the rear thereof, whereupon the screws 34 are applied and the members 12 and 13 are drawn into tight 30 engagement with the mating surfaces of the conduit 14.

While I have shown my improvement as mounted in the upper or signal port of a train pipe coupling head it will be observed that it may be otherwise mounted if desired. The cable C may extend from my improved terminal in one connector head to my improvement on a coupling head at the other end of a car, or such cable may terminate at a junction box on the end of the car thus enabling the train men to cut in with a telephone at any 35 car in a train and convey signals either forward or rearward through the train. It will be observed from the drawings that the face 30 of the member 12 extends flush with the face 10 of the coupling head A and that the plungers 31 lie in the horizontal plane and

either side of the vertical center line of the head A as shown particularly in Figures 2, 3 and 4. The plungers project slightly in advance of the face 30 of the member 12 but are pushed rearwardly against the tension of the springs 33 when opposing coupling heads couple in service. While I have referred to my improvement principally as an electrical means for conveying signals through a train, it may also be used for the purpose of lighting 70 or heating the train or conveying power there-through or effecting telephone communication between the engineer and the conductor at any point in the train.

What I claim as new is:

1. In an automatic train pipe connector, a coupling head having a coupling face, and also having an opening extending therethrough substantially at right angles to said face, a plug in said opening, said plug comprising a front portion and a rear portion respectively insertable in said opening from the front and rear thereof, means for limiting the extent to which the parts of the terminal may be inserted in said opening, means for connecting the two parts of the plug when inserted in the opening, a plurality of contacts slidably mounted in the front portion of the plug and normally projecting beyond the coupling face of the head when the plug 90 is in position in said opening, and electric conductors connected to said contacts.

2. In a construction of the kind described, the combination with a coupling head provided with an opening adapted to interchangeably receive a train pipe hose and a contact plug and having a coupling face, of a contact plug mounted in said opening, said plug comprising a front portion and a rear portion respectively insertable in said opening from the front and rear of the head, means for rigidly connecting the two parts of the plug when inserted in said opening, and a movable contact carried by said plug and normally projecting beyond said coupling 100 face when the plug is in position in the head.

3. In an automatic train pipe connector, a coupling head having a coupling face and also having an opening extending therethrough substantially at right angles to said 115 face, a contact plug in said opening, said plug comprising a front portion and a rear portion respectively insertable in said opening from the front and rear of the head, means for rigidly connecting the two parts of the plug 120 when inserted in said opening, a contact slidably carried by said plug and normally projecting beyond the coupling face of the head when the plug is in position in the head, and a conductor connected to said contact.

In testimony whereof I hereby affix my signature.

JOSEPH V. ROBINSON.
